UNITED STATES PATENT OFFICE.

HAROLD A. RICHARDSON, OF STEELTON, PENNSYLVANIA.

DESIGN FOR A DISPLAY-STAND AND HANGER.

No. 39,172.

Specification for Design.

Patented March 3, 1908.

Application filed December 19, 1907. Serial No. 407,266. Term of patent 14 years.

To all whom it may concern:

Be it known that I, HAROLD A. RICHARDSON, a citizen of the United States of America, residing at Steelton, in the county of Dauphin and State of Pennsylvania, have invented a new, original, and ornamental Design for Display-Stands and Hangers, of which the following is a specification, reference being had to the accompanying drawing, forming part thereof.

Figure 1 is a front view and Fig. 2 a side elevation of the display stand and hangers, showing my new design.

I claim:

The ornamental design for a display stand and hanger, as shown.

HAROLD A. RICHARDSON.
